UNITED STATES PATENT OFFICE.

AUGUST HILDT, OF NEW YORK, N. Y., ASSIGNOR TO L. DRYFOOS & CO.,
OF SAME PLACE.

DESIGN FOR QUILTING.

SPECIFICATION forming part of Design No. 16,563, dated March 9, 1886.

Application filed December 23, 1885. Serial No. 186,584. Term of patent 7 years.

To all whom it may concern:

Be it known that I, AUGUST HILDT, of the city, county, and State of New York, have invented a new and original Design for Quilting, of which the following is a specification, reference being had to the accompanying drawing, which represents a strip of fabric quilted in accordance with my invention.

The design consists of alternate rows or groups of diamond or lozenge shaped figures a and six-sided figures b, whose longer sides are parallel, and which terminate in tapering or pointed ends. These two sets of figures meet and join one another at the points 1, the 15 sides of the figures b, which form the tapering ends of those figures, being a prolongation of the adjoining sides of the figures a contiguous to them.

The diamonds a are interposed between adjoining rows of the six-sided figures b, the arrangement being such that the diametrically-opposite points a' of the diamonds shall join the similarly-located points b' of the figures b of both rows. The diamonds in each row or group also join one another at the points 2.

What I claim, and desire to secure by Letters Patent, is—

The design for quilting fabric, consisting of alternate rows of diamond or lozenge shaped figures a and six-sided figures b, with the points 3 b' of the corresponding figures, b, of two adjoining rows directly opposite to each other, and with the diamonds of each row joined at their points a' to the points b' of figures b in the two adjoining rows, as described and shown.

In testimony whereof I have hereunto signed my name this 22d day of December, 1885.

AUGUST HILDT.
